Specification for Design.

Patented Apr. 6, 1915.

Application filed December 28, 1914. Serial No. 879,406. Term of patent 7 years.

To all whom it may concern:

Be it known that I, WILLIAM C. HEITZMANN, a citizen of the United States, residing at Union City, in the county of Randolph and State of Indiana, have invented a new, original, and ornamental Design for Vehicle-Bodies, of which the following is a description, reference being had to the drawing forming part of this application, whereby is shown in perspective a vehicle-body embodying the present design.

This invention relates to a new, original and ornamental design for vehicle bodies in general, either horse-drawn or power-driven, mounted upon wheels or runners, but it is particularly designed, arranged and adapted for ornamenting the exterior of driving buggies as shown by the drawing.

The present invention therefore comprises a vehicle body having a body portion proper, configured by vertically arranged adjacent and uniform corrugations 1 extending around the entire structure, sides and ends. Surmounting this body portion as shown, is a carriage seat harmoniously corrugated upon its outer surface, both back and sides, as at 2, these corrugations also being substantially vertical in their arrangement, but following the general contour of said seat, the back of which may be described as a shell pattern.

The foregoing being a general description of this invention, what I now claim is:

The ornamental design for a vehicle body, as shown and described.

In testimony whereof I affix my signature in the presence of two subscribing witnesses.

WILLIAM C. HEITZMANN.
